UNITED STATES PATENT OFFICE.

HARRY F. WOERNLEY, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

WEATHER-PROTECTOR FOR COUPLINGS.

1,400,649.

Specification of Letters Patent. Patented Dec. 20, 1921.

Application filed December 6, 1918. Serial No. 265,574.

To all whom it may concern:

Be it known that I, HARRY F. WOERNLEY, a citizen of the United States, residing at Pittsburgh, in the county of Allegheny and 5 State of Pennsylvania, have invented new and useful Improvements in Weather-Protectors for Couplings, of which the following is a specification.

This invention relates to electric train 10 wire couplings, and has for its principal object to provide a device for protecting the electric contacts against the weather.

In the accompanying drawings, Figure 1 is a plan view of a combined car, air, and 15 electric coupler head, partly sectioned, and showing a protecting device, constructed in accordance with my invention, applied thereto; Fig. 2 a face view of the coupler head shown in Fig. 1; Fig. 3 a plan view of 20 a coupler head, with a modified form of protecting device applied thereto; Fig. 4 a face view of the coupler head shown in Fig. 3; Fig. 5 a view, showing the blank from which 25 the protecting device shown in Figs. 3 and 4 is formed; and Fig. 6 an isometric projection of the protecting device shown in Figs. 3 and 4.

According to the construction shown in 30 Figs. 1 and 2 of the drawings, the protecting device 1 is made of wood and is shown applied to a coupler head 2 of the well known tight lock type having the usual pivoted lock 3 for clamping counterpart coupler heads together.

35 Embodied in the coupler head 2 are electric contacts 4 adapted to engage corresponding contacts in a counterpart coupler head when in coupled position.

The protecting device 1 is made semi- 40 circular to conform to the circular contour of the portion 5 which contains the contacts 4 and is provided with a tongue 6 which is adapted to fit into a recess 7 which happens to exist between the contact portion 5 and 45 the coupler head proper.

When the coupler head is in its uncoupled position and it is desired to protect the electric contacts from the weather, the protecting device 1 is applied, so that the tongue 50 6 engages within the recess 7. The pivoted lock 3 is pushed back against the resistance of spring 17 acting through the rod 18, and the protecting device 1 is then held in posi-

tion by the pivoted lock 3 pressing the device against a projecting shoulder or ledge 55 19 of the coupler head, as shown in Fig. 1.

The protecting device may also be employed to cover the electric contacts in shipping coupler heads from the factory or otherwise.

In order to insure insulation of the contacts 4 from each other, the inner face of the protecting device 1 may be recessed and a section 8 of insulation may be inserted for 60 engaging the contacts, as shown in Fig. 1. 65

The protecting device 9 shown in Figs. 3 and 4 of the drawings, is made of sheet steel and may be formed up from a cut blank 10 such as is shown in Fig. 5.

The upper portion of the blank 10 is 70 folded inwardly at the dotted lines A and B, and a portion 11, which is partly cut from the blank at the lines C and D is bent outwardly on the dotted line E at an angle approximating the angle of the electric contact face of the coupler. 75

The portion 11 is held in position by an angle clip 12 while at the left hand edge of the device there is secured a section of angle iron 13.

Attached to the angle iron 13 is a clip 14, yielding held in position by a coil spring 15 mounted on a bolt 16, which extends through a hole in the angle iron 13.

The device 9 is applied to the coupler 85 head by slipping the clip 14 over a projection 21 of the coupler head and then pressing the device into position, with the portion 11 engaging the ledge 19 of the coupler head, as shown in Fig. 3. 90

The above described form of protecting device may also cover the air conduit terminals 22, as shown in Fig. 4, so as to prevent the entrance of dirt and moisture into the air pipes. 95

The protecting device may be removed by pulling at the finger piece 20, so as to disengage the clip 14 from the projection 21.

Having now described my invention, what I claim as new, and desire to secure by Letters Patent is:—

1. The combination with a coupler head having electric contacts and a projecting ledge and provided with a yielding pivoted lock for clamping counterpart coupler heads 105 together, of a device for protecting the elec-

tric contacts from the weather and mounted in position between said ledge and said pivoted lock.

2. The combination with a coupler head having electric contacts and a projecting ledge and provided with a spring pressed pivoted lock for clamping counterpart coupler heads together, of a manually de-

tachable device for application to the coupler head to protect the contacts from the weather and inserted in position between said ledge and said pivoted lock.

In testimony whereof I have hereunto set my hand.

HARRY F. WOERNLEY.
